(57) **CLAIM**

The ornamental design for a scoring wristband as shown and described.

DESCRIPTION

FIG. 1 is a top perspective view of the first embodiment of a scoring wristband showing our new design;

FIG. 2 is a top perspective view of the first embodiment thereof;

FIG. 3 is a bottom perspective view of the first embodiment thereof;

FIG. 4 is a front view of the first embodiment thereof;

FIG. 5 is a rear view of the first embodiment thereof;

FIG. 6 is a left view of the first embodiment thereof;

FIG. 7 is a right view of the first embodiment thereof;

FIG. 8 is a top view of the first embodiment thereof;

FIG. 9 is a bottom view of the first embodiment thereof;

FIG. 10 is a top perspective view of the second embodiment of the scoring wristband showing our new design;

FIG. 11 is a top perspective view of the second embodiment thereof;

FIG. 12 is a bottom perspective view of the second embodiment thereof;

FIG. 13 is a front view of the second embodiment thereof;

FIG. 14 is a rear view of the second embodiment thereof;

FIG. 15 is a left view of the second embodiment thereof;

FIG. 16 is a right view of the second embodiment thereof;

FIG. 17 is a top view of the second embodiment thereof;

FIG. 18 is a bottom view of the second embodiment thereof;

FIG. 19 is a top perspective view of the third embodiment of the scoring wristband showing our new design;

FIG. 20 is a top perspective view of the third embodiment thereof;

FIG. 21 is a bottom perspective view of the third embodiment thereof;

FIG. 22 is a front view of the third embodiment thereof;

FIG. 23 is a rear view of the third embodiment thereof;

FIG. 24 is a left view of the third embodiment thereof;

FIG. 25 is a right view of the third embodiment thereof;

FIG. 26 is a top view of the third embodiment thereof;

FIG. 27 is a bottom view of the third embodiment thereof;

FIG. 28 is a top perspective view of the fourth embodiment of the scoring wristband showing our new design;

FIG. 29 is a top perspective view of the fourth embodiment thereof;

FIG. 30 is a bottom perspective view of the fourth embodiment thereof;

FIG. 31 is a front view of the fourth embodiment thereof;

FIG. 32 is a rear view of the fourth embodiment thereof;

FIG. 33 is a left view of the fourth embodiment thereof;

FIG. 34 is a right view of the fourth embodiment thereof;

(Continued)

FIG. 35 is a top view of the fourth embodiment thereof; FIG. 36 is a bottom view of the fourth embodiment thereof; FIG. 37 is a top perspective view of the fifth embodiment of the scoring wristband showing our design; FIG. 38 is a top perspective view of the fifth embodiment thereof; FIG. 39 is a bottom perspective view of the fifth embodiment thereof; FIG. 40 is a front view of the fifth embodiment thereof; FIG. 41 is a rear view of the fifth embodiment thereof; FIG. 42 is a left view of the fifth embodiment thereof; FIG. 43 is a right view of the fifth embodiment thereof; FIG. 44 is a top view of the fifth embodiment thereof; and, FIG. 45 is a bottom view of the fifth embodiment thereof. The broken lines in FIGS. 1, 10, 19, 28 and 37 showing a human hand represent environmental subject matter only and form no part of the claimed design. The dot-dot-dash lines represent a symbolic cut line and form no part of the claimed design.
